[57] CLAIM

The ornamental design for an oil recycling container, as shown and described.

DESCRIPTION

FIG. 1 is a top perspective view showing my new design;

FIG. 2 is an end elevation view of one end thereof;

FIG. 3 is a side elevation view of one side thereof;

FIG. 4 is an end elevation view of the opposite end thereof;

FIG. 5 is a side elevation view of the opposite side thereof;

FIG. 6 is a top plan view thereof;

FIG. 7 is a bottom plan view thereof;

FIG. 8 is a cross-sectional view taken along line 8—8 of FIG. 6; and,

FIG. 9 is a cross-sectional view taken along line 9—9 of FIG. 6 thereof.

The broken line showing of the cap is for illustrative purposes only and forms no part of the claimed design.
